HALBERT K. HITCHCOCK, OF PITTSBURGH, PENNSYLVANIA.

METHOD OF AND APPARATUS FOR APPLYING FINELY-DIVIDED MATERIAL TO GRINDING AND SMOOTHING MECHANISM.

1,311,517.

Specification of Letters Patent. Patented July 29, 1919.

Application filed August 9, 1915. Serial No. 44,622.

To all whom it may concern:

Be it known that I, HALBERT K. HITCHCOCK, a resident of Pittsburgh, in the county of Allegheny and State of Pennsylvania, have invented a new and useful Improvement in Methods of and Apparatus for Applying Finely-Divided Material to Grinding and Smoothing Mechanism, of which the following is a specification.

10 This invention relates to method and apparatus for grading abrasives and supplying the same to grinding machines, and particularly for grading sand or other abrading material and supplying the same 15 to apparatus for grinding or finishing plate glass.

One object of the invention is to improve the grinding and finishing operations by more accurate classification or grading of 20 the abrasive material, to thereby reduce the total time required for grinding and finishing a single side of glass and secure more efficient operation and an improved product. A further object of the invention is to provide 25 a method and apparatus which produces in a single vessel a cleaner and more accurate separation or classification of the different grades of abrading material and avoids contamination of one grade by any 30 other grade, and also produces a denser mixture of the abrading material with the liquid in which it is suspended, so that the grinding and finishing operations can be carried out more economically, with less liquid, less 35 handling of the material, in a shorter time and with as simple an apparatus as possible. A further object of the invention is to provide 40 a method and apparatus enabling the grading operation to be carried on under uniform conditions with the production of sharply differentiated grades of material which are maintained at various levels in the grading vessel, so that the operator can rely upon the accuracy of each grade of abrading 45 material at the various levels in the grading vessel. A further object of the invention is to provide a method and apparatus in which the abrading material is supplied to the grading vessel in suspension in a liquid at a 50 level intermediate its bottom and the upper level of liquid therein, so as to secure a sharp classification or grading of the material and prevent contamination of one grade by another, and in which the grading operation 55 is produced by the upward flow or travel of

a stream of clear liquid introduced to said vessel, so that the conditions for grading in said vessel are maintained substantially uniform and are independent of the exact rate of supply of the abrading material to said vessel and of the speed of operation of the supply pump. A further object of the invention is to secure a dense mixture, especially of the finer grades, by eliminating from the various levels in the grading vessel the superfluous liquid, so as to maintain a sufficient supply of the finer grades in suspension without the necessity of collecting the finer grades of abrading material in a separate grading vessel and settling the same, thereby securing more rapid and efficient operation of the apparatus during finishing. A further object of the invention is to provide an improved method and apparatus wherein the rough grinding is carried on in a continuous cycle of circulation with the material constantly in suspension in a liquid, the finer grades being collected in the same grading vessel and condensed by elimination of the surplus liquid and subsequently conducted to the grinding apparatus for the finishing operation. Further objects of the invention are in part obvious and in part will appear more in detail hereinafter.

In the drawings, Figure 1 represents in diagrammatic sectional elevation one form of apparatus embodying the invention; Fig. 2 is a detail sectional elevation, on a larger scale, through the grading vessel; Fig. 3 is a plan view thereof; and Fig. 4 is a diagrammatic sectional elevation of another form of apparatus embodying the invention.

Referring to the drawings, 1 indicates a grinding table equipped with a pair of runners 2 of the usual form. Said table is surrounded by a gutter 3 communicating with a conduit 4 which conveys the liquid and used abrading material over a screen 5 to a sump or pit 6, having the usual overflow 6^a for elimination of the excess liquid, the slimes and the material too fine for further use. From the sump the mixture is withdrawn through a pipe 7 by the centrifugal pump 8 and delivered to the grading vessel 9. The grading vessel is arranged to grade the new material, regrade the used material and separate the various grades and maintain them at different levels, therein, from which levels the several grades may be withdrawn independently and in any de-

sired sequence through several withdrawal pipes 10, 11 and 12 to a trough 13 for conducting the abrading material by gravity to the grinding table 1. One of said pipes, 5 such as the pipe 11, may be a flexible tube long enough to reach to the bottom or top of the grading vessel and having its free end weighted and connected to suitable devices on the outside of the grading vessel for 10 moving it to any level therein, so that mixture can be withdrawn through said pipe from any level in the grading vessel. One suitable arrangement for this purpose is shown in my prior application, Serial No. 15 806,594, filed December 13, 1913, and therefore requires no further description. The fresh abrading material or sand can be added to the system at any point, but preferably is supplied directly to the sump or pit 20 6 from a hopper 14 fed by a clam shell bucket or other suitable device, preferably being added in measured batches, one before (or at least during the first part of) each grinding operation. The grading vessel is 25 provided with the usual overflow pipe 16, for carrying away the scum, superfluous liquid, and abrading material too fine for further use, said pipe leading to the gutter 3 so that the liquid carried thereby can be 30 utilized for washing out the gutter and ditches around the table. So far as described to this point the apparatus may be of the same general kind shown, for example, in Fig. 1 of my prior Patent No. 35 1,089,705, dated March 10, 1914.

According to the present invention the grading operation in the vessel 9 is carried out in a manner to utilize the general principles set forth in my prior Patent 1,100,302, 40 dated June 16, 1914, and grades or classifies the material while in suspension in a liquid in the grading vessel by the action of a current of liquid having an upward flow or travel relative to a downward movement 45 of the material, which separates and classifies the several grades in different strata in said vessel, the finer grades near the top and the coarser grades near the bottom. The material to be graded has heretofore 50 been introduced into the grading vessel either at its bottom, as in my Patent 1,100,302, or at the upper level of liquid in said vessel. When introduced at the bottom the finer grades are carried upwardly by the 55 upward flow or travel of the liquid relative to the material and pass in turn the outlets through which the several coarser grades are withdrawn. Some of the fine material therefore unavoidably passes out through 60 the various openings when the apparatus is run continuously. On the other hand, when the abrading material is introduced at the upper level of liquid in the grading vessel the coarse material falls past the outlets for 65 the several finer grades, so that said grades

are contaminated by some of the coarser material, or, a considerable time must be allowed for the coarse material to reach equilibrium at its proper levels before the fine material can be withdrawn to the grinding 70 apparatus during finishing.

In the present invention the material to be graded is introduced into the grading vessel at a level intermediate its bottom and the upper level of liquid therein, thereby 75 enabling the coarser material to travel downwardly against the rising current of liquid and the finer grades to travel upwardly with said current, so that all grades of material find their proper levels without contaminating 80 one grade with material from another. The mixture of liquid and finely divided material to be graded is preferably introduced into the grading vessel in an upwardly traveling stream, for example, 85 through a nozzle 17 supplied by the pump 8 and extending into said vessel, preferably upwardly through its bottom, and terminating at a level intermediate its bottom and the upper level of liquid therein. The bottom of the grading vessel is provided with an inlet 18 for a clear liquid supply to produce or augment the upward flow or travel 90 of the liquid relative to the material and produce the grading action. This clear liquid supply is preferably under a sufficiently high pressure so that it produces the effective upward flow or travel of the liquid for the grading operation, and the exact speed of operation of the pump 8 is 95 more or less immaterial, as slight variations in the speed of said pump do not appreciably affect the velocity of upward flow of the liquid which produces the grading action. Moreover, a pump operated by a 100 motor on a constant potential circuit runs practically at constant speed. The density of the grinding mixture is regulated by the auxiliary clear water supply, which is only a small percentage of the total volume of 105 liquid. Consequently the pump can be run at practically constant speed without any elaborate apparatus to secure exact regulation.

The outlet for the coarsest grade or grades 115 through the pipe 10 may be located at any suitable level, but is preferably located at a level between the inlet 18 for the clear liquid supply and the mouth of the nozzle 17 where the material to be graded is introduced to the grading vessel, so that said outlet lies in a zone or stratum not traversed by any of the finer grades. Consequently, an extra clean coarse grade or grades can be withdrawn from this region of the grading 120 vessel. The clear liquid supply travels upwardly through the grading vessel with the mixture of liquid and material to be graded, but the velocity of upward travel of the liquid relatively to the downward flow of 125

the material at and near the inlet for the mixture is not sufficient to carry any of the coarser particles upwardly, but is merely sufficient to lift the finer grades to their proper levels in the grading vessel.

In operation of this system the pump 8 supplies abrading material in suspension in the liquid from the sump or pit to the grading vessel and the grading operation is carried on continuously so that a sufficient supply of graded abrading material is always collected at the proper levels in the grading vessel. During the rough grinding operation the coarse material in suspension in the liquid is withdrawn through pipe 10 and conducted by trough 13 to the grinding table and is thrown into the gutter 3 and flows through ditch 4 to the sump 6, where the excess water and slimes are eliminated through the over flow 6^a, and from which the mixture is returned to the grading vessel to be regraded therein. The grading and regrading with the material constantly in suspension in a liquid, and the cycle of circulation from the grading vessel to and from the grinding apparatus go on continuously until the rough grinding or facing operation is finished. During this operation the finer grades in the grading vessel are collected for use during the finishing operation, but without contamination by the coarser grades, which are supplied to the grading vessel at a level below the finer grades and therefore do not contaminate the same. When the rough grinding or facing is concluded the supply of coarse material through the pipe 10 is shut off, and the finishing is effected by withdrawing the several finer grades through the pipes 11 and 12 in succession or in any desired sequence and conducting them to the table. During such finishing these finer grades may be circulated to the grinding apparatus and back to the grader, or not, as desired. At the conclusion of the rough grinding or facing operation the supply of material to the grading vessel from the sump may be discontinued after a sufficient time has elapsed to collect the proper quantity of finer grades in the grading vessel, but preferably is continued without interruption during both rough grinding and finishing so as to maintain in the grading vessel at all times as much of the abrading material as possible.

The finishing operation is more advantageously effected when the mixture of material has a certain density, which density is greater than that ordinarily found in any single grader grading apparatus heretofore used. Suitable means is therefore provided for eliminating the surplus liquid from the various levels in the grading vessel without withdrawing any of the useful fine material therefrom, so as to secure the desired density

and distribution of the mixture. In the apparatus shown the grading vessel 9 has a conical lower portion 20 which produces a decreasing upward velocity of flow or travel of the liquid relative to the material 70 at the various levels therein to collect or classify the coarse grades, and a cylindrical upper portion 21 which serves as a supplemental grader for the finer grades superposed upon the lower or conical portion of 75 the vessel, and which traps various finer grades at different levels therein. Within the cylindrical upper portion 21 of the grading vessel is located an annular gutter or trough 22, to receive an overflow of the 80 liquid in the grading vessel over the inner wall of the gutter. The bottom of the gutter is inclined downwardly in opposite directions circumferentially of the grading vessel from one side to the other, and at its 85 lowest part, said gutter communicates through an opening in its side wall and through the side wall of the tank with the overflow pipe 16. Within the cylindrical portion of the grading vessel and at different levels therein are located a series of 90 small hollow dehydrating cones 24 communicating with upwardly extending pipes 25 discharging into the gutter 22, said pipes being provided with suitable regulating 95 valves 26.

When the valves 26 are fully closed no liquid or abrading material can flow upwardly into or through the cones 24, but if said valves are opened the liquid flows out 100 through the cones 24 and pipes 25 into the gutter 22, the velocity of flow increasing with the size of the opening through said valves. When liquid is flowing upwardly through the cones 24 and pipes 25 the velocity of flow increases from the bottom of the cones upwardly and reaches a maximum at the pipe 25. Each valve 26 is adjusted so that the velocity of flow in its cone at a level between its top and bottom, say at the 110 line B, Fig. 2, is equal to the velocity of flow of the mixture in the grading vessel at the level A of the bottom of the cone. The velocity of flow of the liquid between levels A and B is therefore something less than 115 at said levels and is insufficient to lift any abrading material lying in equilibrium at the level A into the cone 24. Consequently each cone abstracts or removes from the grading vessel at its particular level some 120 of the liquid of the mixture, but without removing any abrading material normally belonging in that zone.

The discharge of liquid at each of the cones 24 progressively reduces the upward 125 velocity in the cylindrical portion 21 of the grading vessel by a series of steps, so that the finer grades are separated into groups distributed at various levels in the grading vessel. At each level a certain grade or size 130

of material between definite limits gradually accumulates, each grade becoming more and more dense as the dehydrating operation proceeds. The grades become gradually finer and finer upwardly at the different levels in the vessel as the interstitial velocity of the liquid decreases. The several zones between the bottoms of the inverted cones 24 therefore form a series of traps, each accumulating its own particular grade of fine material, and the cones condense it by abstracting the superfluous liquid therefrom, so that these finer grades are collected and stored during the several cycles of the rough grinding operation for later use during finishing. The character and position of these grades can be regulated by means of the valves 26.

The superfluous liquid withdrawn through the several cones 24, together with the overflow over the inner wall 23 of the trough 22 flows through the pipe 16 to the gutter surrounding the grinding table and is utilized for washing the used abrading material back into the sump, being finally eliminated from the system through the overflow from the sump.

Fig. 4 illustrates another form of apparatus embodying the invention and also serving to regulate the supply of abrading material to the grading vessel by variations in the density of the mixture in said vessel, so as to maintain said density substantially uniform, prevent variation in the grading conditions in the vessel, and insure the maintenance of accurate grades of material at the different levels in the grading vessel throughout the entire operation, as more fully described in my application for method and apparatus for grading finely divided material, of even date herewith, Serial No. 44623. In this form of the invention the material to be graded is delivered in suspension in a liquid to the grading vessel through a depending pipe or conduit 30 whose bottom opening is immersed in the liquid in said vessel at a suitable level intermediate its bottom and the upper level of liquid therein, for example, at a level intermediate the levels of the openings to the withdrawal pipes 10 and 11. The bottom of the grading vessel is provided with the inlet 18 for a clear liquid supply to produce a definite upward flow in the apex of the cone and to augment the upward flow of liquid relative to the material in the upper part. The coarse particles in the material to be graded passing in through the pipe 30 fall downwardly against the rising current from the inlet 18, the velocity of said current being sufficient to lift the finer particles of material before they have a chance to drop to the outlet or outlets for the coarser grades. Consequently a very clean coarse grade of material may be withdrawn through the

pipe 10. The finer grades rise to the levels of the outlets for the finer grades, but no coarse material is carried up with the fine, so that the several finer grades withdrawn from the pipes 11 and 12 are clean and free from contamination by the coarser grades.

The material to be graded is supplied to the pipe 30 from a supply box or vessel 35, located at the upper end of the pipe 30 and provided with a suitable hand-operated valve 36 for controlling the flow of material from the vessel 35 to the pipe 30. Material is supplied to the vessel 35 by the centrifugal pump 8, the inlet to which is immersed in the sump or pit 6, as before. Vessel 35 is also supplied with an overflow pipe 39 delivering to the sump and connected to said vessel 35 at a level above the valve 36, so that when said valve is open a constant head or level of liquid is maintained in the supply vessel 35 at the level of the overflow pipe 39.

In operation of this system, during rough grinding, the valve 36 is open and the material delivered by the pump passes downwardly to the grading vessel through the pipe 30, the excess flowing back to the sump through the overflow 39. The density of the mixture in the grading vessel varies from time to time as the total quantity of material therein to be graded increases or diminishes, and the total quantity of material in the grading vessel varies with the supply thereto and the amounts of the various grades withdrawn at the different outlets. While the downwardly moving stream of mixture introduced into the grading vessel is independent of or separated from the body of mixture therein, the density of the body of mixture in the vessel nevertheless affects the velocity of flow in the stream of mixture being supplied to said vessel. This is due to the fact that the column of mixture in the pipe or conduit 30, which has a constant head or pressure, is balanced against a similar column of liquid in the body of mixture in the grading vessel, but at a lower head or pressure. If the weight or pressure produced by the body of mixture in the grader is less than that of the column of liquid in the pipe or conduit 30 the preponderating weight of the mixture in the latter produces a more rapid downward flow thereof, while, on the other hand, if the weight or pressure produced by the mixture in the grading vessel is greater than that in the pipe or conduit 30 through which the mixture is introduced, then the preponderating effect of the body of liquid in the grading vessel tends to produce an upward flow of the mixture in the pipe 30. This effect partially or completely counteracts the normal downward flow of the mixture in the delivery pipe 30 to replace the mixture being withdrawn from the grading vessel and

causes more or less of the mixture being supplied to the grader to pass out through the overflow 39 and back to the sump, thus shunting the superfluous material around the grader. Consequently, the downward flow or travel of the mixture through the delivery pipe or conduit 30 varies inversely with the density of the body of the mixture in the grading vessel, increasing as the density decreases and decreasing as the density increases, and tends to automatically govern or regulate the mixture being graded in the vessel so that it is maintained at a more nearly uniform or fixed density. This particular form of the invention is not claimed here, but forms the subject matter of my pending application Serial No. 44623, of even date herewith.

In both forms of the apparatus shown, during the rough grinding operation the coarse material is circulated constantly in suspension in the liquid from the grading vessel to the grinding apparatus, thence to the sump and up again into the grading vessel, the circulation being continued uninterruptedly until the grinding operation is finished. The supply of coarse material from the grader to the grinding apparatus is then shut off. During the entire rough grinding operation the fine material is collected and dehydrated in the upper strata of the grading vessel ready for use during the finishing operation, which can begin immediately after the conclusion of the rough grinding operation, without waiting to collect a sufficient supply of the finer grades. If desired, the supply of material to the grading vessel can be discontinued during the finishing operation, although it is preferably continued without interruption at all times so as to store the abrading material in the grading vessel rather than in the sump. The accurate classification of the material by the method and apparatus described produce such an efficient grinding action as to reduce the total quantity of abrading material and liquid required, and as a consequence it is usually necessary to circulate the abrading material from the sump to the grader continuously to insure the production of a sufficient amount of fine material to complete the finishing operation. If a large quantity of abrading material is in the system, however, the supply of abrading material to the grader during the finishing operation is not essential.

In the apparatus shown in Fig. 4 the supply of abrading material to the grader is discontinued by closing the valve 36, but without stopping the pump 8, so that the abrading material is delivered by the pump to the supply vessel 35 and returns directly to the sump, thus bypassing it around the grading vessel. In both forms of apparatus shown the flow of clear liquid to the bot-

tom of the grading vessel for producing or augmenting the upward flow or travel of liquid relative to the material is continued during the entire grinding and finishing operations. The dehydrating cones operate continuously during all stages of the grinding and finishing operations and serve to constantly collect and condense the finer grades in the upper portion of the grading vessel.

What I claim is:—

1. The method described, consisting in separating abrading material mixed with a liquid in a vessel into different grades, withdrawing said grades in any desired sequence and conducting the same to grinding mechanism, returning the same to the grading vessel and introducing the same into said vessel at a level intermediate its bottom and the upper level of liquid therein, simultaneously eliminating surplus liquid from various levels in said grading vessel, and introducing liquid into said vessel below the level at which the abrading material is supplied thereto.

2. The method described, consisting in separating abrading material mixed with a liquid in a vessel into different grades, withdrawing said grades in any desired sequence and conducting the same to grinding mechanism, returning the same to the grading vessel and introducing the same into said vessel at a level intermediate the coarsest and finest grades withdrawn therefrom, and simultaneously eliminating surplus liquid from various levels in said vessel while retaining therein the abrading material at said levels.

3. The method described, consisting in separating abrading material mixed with a liquid in a vessel into different grades, withdrawing said grades in any desired sequence and conducting the same to grinding mechanism, returning the same to the grading vessel and introducing the same into said vessel at a level intermediate the coarsest and finest grades withdrawn therefrom, simultaneously eliminating surplus liquid from various levels in said vessel while retaining therein the abrading material at said levels, and simultaneously introducing liquid into said vessel below the level at which the abrading material is supplied thereto.

4. The method described, consisting in separating abrading material mixed with the liquid in a vessel into different grades, withdrawing said grades in any desired sequence and conducting the same to grinding mechanism, returning the same to the grading vessel and introducing the same into said vessel at a level intermediate the coarsest and finest grades withdrawn therefrom, and eliminating the surplus liquid from various levels in said grading vessel while retaining therein the abrading mate-

rial at said levels, said grading, regrading, circulation and elimination being carried on in an uninterrupted cycle with the material constantly mixed with the liquid.

5. The method described, consisting in separating abrading material mixed with a liquid in a vessel into different grades, withdrawing said grades in any desired sequence and conducting the same to grinding mechanism, returning the same to the grading vessel and introducing the same into said vessel at a level intermediate the coarsest and finest grades withdrawn therefrom, eliminating the surplus liquid from various levels in said grading vessel while retaining therein the abrading material at said levels, said grading, regrading, circulation and elimination being carried on in an uninterrupted cycle with the material constantly mixed with the liquid, and simultaneously introducing liquid into said vessel below the level from which the coarse material is withdrawn.
6. The method described, consisting in separating abrading material mixed with a liquid in a vessel into different grades, withdrawing the coarser grades separately and independently and conducting the same to the grinding mechanism during the rough grinding operation, returning the same to the grading vessel and introducing the same into said vessel at a level intermediate the level of the coarsest and finest grades withdrawn therefrom, said grading, regrading and circulation being carried on in an uninterrupted cycle with the material constantly mixed with the liquid, condensing the finer grades in said grading vessel, and withdrawing the same to the grinding apparatus during the finishing operation.
7. The method described, consisting in separating abrading material mixed with a liquid in a vessel into different grades, withdrawing said grades in any desired sequence and conducting the same to grinding mechanism, and returning the same to the grading vessel and introducing the same into said vessel at a level intermediate the coarsest and finest grades withdrawn therefrom.
8. The method described, consisting in separating abrading material mixed with a liquid in a vessel into different grades, withdrawing said grades in any desired sequence and conducting the same to grinding mechanism, returning the same to the grading vessel and introducing the same into said vessel at a level intermediate the coarsest and finest grades withdrawn therefrom, and simultaneously introducing liquid into said vessel below the level from which the coarse material is withdrawn.
9. The method described, consisting in separating abrading material mixed with a liquid in a vessel into different grades, withdrawing said grades in any desired sequence and conducting the same to grinding mechanism, returning the same to the grading vessel and introducing the same into said vessel at a level intermediate the coarsest and finest grades withdrawn therefrom, and simultaneously introducing liquid into said vessel below the level from which the coarse material is withdrawn.
10. The method described, consisting in separating abrading material mixed with a liquid in a vessel into different grades, withdrawing said grades in any desired sequence and conducting the same to grinding mechanism, returning the same to the grading vessel and introducing the same into said vessel at a level intermediate the coarsest and finest grades withdrawn therefrom, and simultaneously introducing liquid into said vessel below the level from which the coarse material is withdrawn, said grading, regrading and circulation being carried on in an uninterrupted cycle with the material constantly mixed with the liquid.
11. The method described, consisting in separating abrading material mixed with a liquid in a vessel into different grades, withdrawing said grades independently from different levels and conducting the same to grinding mechanism, and returning the same to the grading vessel and introducing the same into said vessel in a rising stream at a level intermediate the levels of the coarsest and finest grades withdrawn therefrom.
12. The method described, consisting in separating abrading material mixed with a liquid in a vessel into different grades, withdrawing said grades independently from different levels and conducting the same to grinding mechanism, returning the same to the grading vessel and introducing the same into said vessel in a rising stream at a level intermediate the levels of the coarsest and finest grades withdrawn therefrom, and simultaneously introducing liquid into said vessel below the level from which the coarse material is withdrawn.
13. The method described, consisting in subjecting abrading material mixed with a liquid to an upward flow or travel of the liquid relative to the material in a vessel and thereby separating the material into grades, introducing the material into the grading vessel at a level intermediate the levels of the coarsest and finest grades withdrawn therefrom, simultaneously withdrawing coarse material from a level below the level at which the material is introduced into said vessel and conducting the same to the grinding mechanism, and returning the used material in suspension in a liquid to the grading vessel.
14. The method described, consisting in subjecting abrasives to an upward flow or

travel of the liquid relative to the abrasives in a vessel, and thereby separating the same into grades, introducing the abrasive into said vessel at a level intermediate the levels 5 of the coarsest and finest grades withdrawn therefrom, withdrawing coarse abrasive from said vessel at a point below the introduction of the abrasive into said vessel and conducting the same to the grinding apparatus, and introducing liquid into said vessel below the level of the introduction of the abrasive thereto.

15. The method described, consisting in subjecting abrasive to an upward flow of travel of the liquid relative to the material in a vessel and thereby separating the abrasive into grades, withdrawing the coarse material from the bottom of said vessel and conducting the same to the grinding mechanism, returning the used material from the grinding mechanism to said grading vessel and introducing the returned abrasive to the grading vessel at a level intermediate the levels of the coarsest and finest grades withdrawn therefrom and repeating the circulation from the grading vessel to the grinding mechanism and return.

16. The method described, consisting in subjecting abrasive to an upward flow or travel of the liquid relative to the material in a vessel and thereby separating the abrasive into grades, withdrawing the coarse material from the bottom of said vessel and conducting the same to the grinding mechanism, returning the used material from the grinding mechanism to said grading vessel and introducing the returned abrasive to the grading vessel at a level intermediate the levels of the coarsest and finest grades withdrawn therefrom, introducing clear liquid into said vessel below the point of introduction of the abrasive thereto, and repeating the circulation from the grading vessel to the grinding apparatus and return.

45 17. Apparatus of the character described, comprising in combination, grinding mechanism, a grading vessel, means for producing in said vessel an upward flow or travel of the liquid relative to the material to separate the material into grades, means for conducting different grades independently from said vessel to the grinding mechanism, and means for returning said material in suspension in a liquid from the grinding mechanism to said vessel and introducing the same thereto at a level intermediate the levels of the coarsest and finest grades withdrawn therefrom.

18. Apparatus of the character described, 60 comprising in combination, grinding mechanism, a grading vessel, means for producing in said vessel an upward flow or travel of the liquid relative to the material to separate the material into grades, means for withdrawing different grades independently and in

any desired sequence from said vessel and conducting the same to the grinding mechanism, and means for returning said material from the grinding mechanism and introducing the same into said vessel at a level 70 intermediate the levels at which the coarsest and finest grades are withdrawn therefrom.

19. Apparatus of the character described, comprising in combination, grinding mechanism, a grading vessel, means for producing in said vessel an upward flow or travel of the liquid relative to the material to separate the material into grades, means for withdrawing different grades independently 80 and in any desired sequence and conducting the same to the grinding mechanism, means for returning said material from the grinding mechanism and introducing the same into said vessel at a level intermediate the levels 85 at which the coarsest and finest grades are withdrawn therefrom, and means for supplying liquid to said vessel at a level below the coarsest grade withdrawn therefrom.

20. Apparatus of the character described, 90 comprising in combination, grinding mechanism, a grading vessel, means for producing in said vessel an upward flow or travel of the liquid relative to the material to separate the material into grades, means for conducting 95 different grades independently from said vessel to the grinding mechanism, and means for returning said material in suspension in a liquid from the grinding mechanism to said vessel and introducing the same 100 thereto in a rising stream of mixture at a level intermediate the levels of the coarsest and finest grades withdrawn therefrom.

21. Apparatus of the character described, 105 comprising in combination, grinding mechanism, a grading vessel, means for producing in said vessel an upward flow or travel of the liquid relative to the material to separate the material into grades, and means for returning said material in suspension in a 110 liquid from the grinding mechanism to said vessel and introducing the same thereto in a rising stream of liquid at a level intermediate the levels of the coarsest and finest grades withdrawn therefrom.

22. Apparatus of the character described, 115 comprising in combination, grinding mechanism, a grading vessel, means for producing in said vessel an upward flow or travel of the liquid relative to the material to separate the material into grades, means for returning said material in suspension in a liquid from the grinding mechanism to said vessel and introducing the same thereto in a rising stream of liquid at a level intermediate the 120 levels of the coarsest and finest grades withdrawn therefrom, and means for introducing liquid into said vessel at a level below the level at which the coarsest material is withdrawn therefrom.

23. Apparatus of the character described, comprising in combination, grinding mechanism, a grading vessel, means for producing in said vessel an upward flow or travel of the liquid relative to the material to separate the material into grades, means for returning said material in suspension in a liquid from the grinding mechanism to said vessel and introducing the same thereinto in a rising stream of liquid at a level intermediate the levels of the coarsest and finest grades withdrawn therefrom, and means for eliminating surplus liquid from various levels in said vessel while retaining therein the various grades of abrading materials at said levels.
24. Apparatus of the character described, comprising in combination, grinding mechanism, a grading vessel, means for producing in said vessel an upward flow or travel of the liquid relative to the material to separate the material into grades, means for returning said material in suspension in a liquid from the grinding mechanism to said vessel and introducing the same thereinto in a rising stream of liquid at a level intermediate the levels of the coarsest and finest grades withdrawn therefrom, means for introducing liquid into said vessel at a level below the level at which the material is introduced thereto, and means for eliminating surplus liquid from various levels in said vessel while retaining therein the various grades of abrading materials at said levels.
25. Apparatus of the character described, comprising in combination, grinding mechanism, a grading vessel, means for producing in said vessel an upward flow or travel of the liquid relative to the material to separate the material into grades, means for withdrawing different grades independently from said vessel and conducting the same to the grinding mechanism, means for returning said material from the grinding mechanism and introducing the same into said vessel at a level intermediate the levels at which the coarsest and finest grades are withdrawn therefrom, and a plurality of cones located at different levels in said vessel for withdrawing superfluous liquid from said levels while retaining and condensing the various grades in said vessel.
26. Apparatus of the character described, comprising in combination, grinding mechanism, a grading vessel, means for producing in said vessel an upward flow or travel of the liquid relative to the material to sepa-
- rate the material into grades, means for withdrawing different grades independently and conducting the same to the grinding mechanism, means for returning said material from the grinding mechanism and introducing the same into said vessel at a level intermediate the levels at which the coarsest and finest grades are withdrawn therefrom, and a plurality of cones at different levels in said vessel for supplying liquid to said vessel at a level below the coarsest grade withdrawn therefrom, and a plurality of cones at different levels in said vessel for withdrawing superfluous liquid from said levels while retaining and condensing the various grades in said vessel.
27. Apparatus of the character described, comprising in combination, grinding mechanism, a grading vessel, means for producing in said vessel an upward flow or travel of the liquid relative to the material to separate the material into grades, means for returning said material in suspension in a liquid from the grinding mechanism to said vessel and introducing the same thereinto in a rising stream of liquid at a level intermediate the levels of the coarsest and finest grades withdrawn therefrom, and a plurality of cones located at different levels in said vessel for withdrawing superfluous liquid from said levels while retaining and condensing the various grades in said vessel.
28. Apparatus of the character described, comprising in combination, grinding mechanism, a grading vessel, means for producing in said vessel an upward flow or travel of the liquid relative to the material to separate the material into grades, means for returning said material in suspension in a liquid from the grinding mechanism to said vessel and introducing the same thereinto in a rising stream of liquid at a level intermediate the levels of the coarsest and finest grades withdrawn therefrom, means for introducing liquid into said vessel at a level below the level at which the material is introduced thereto, and a plurality of cones located at different levels in said vessel for withdrawing superfluous liquid from said levels while retaining and condensing the various grades in said vessel.

In testimony whereof, I have hereunto set my hand.

HALBERT K. HITCHCOCK.

Witnesses:

ELBERT L. HYDE,
GLENN H. LERESCLE.
